CLAIM

The ornamental design for a luminaire for a wall partition or the like, as shown and described.

DESCRIPTION

FIG. 1 is a top, left end perspective view of a luminaire for a wall partition or the like showing my new design;

FIG. 2 is a side elevational view thereof, the opposite side being a mirror image;

FIG. 3 is an end elevational view thereof, the opposite end being a mirror image;

FIG. 4 is a top plan view thereof.

FIG. I

FIG.2

FIG.3
